Fig. 10

Fig. 11

FIG. 1 is a side elevational view of a pocket lighter embodying my novel design,

FIG. 2 is a side elevational view of the opposite side of the pocket lighter illustrated in FIG. 1,

FIG. 3 is a front end elevational view,

FIG. 4 is a rear end elevational view,

FIG. 5 is a top plan view,

FIG. 6 is a bottom view,

FIG. 7 is a perspective view viewed from the front and to one side of the lighter,

FIG. 8 is a perspective view viewed from the rear and to one side of the lighter,

FIG. 9 is a side elevational view with the cover in the open position,

FIG. 10 is a view similar to FIG. 9 showing the lighter after the wick has been ignited, and

FIG. 11 is a view in perspective looking from the front and one side of the lighter with the cover in the raised position.

The flame is shown in broken lines in FIG. 10 for illustrative purposes only.

I claim:

The ornamental design for a pocket lighter, as shown and described.
